UNITED STATES PATENT OFFICE.

PETER WELIN, OF WORCESTER, MASSACHUSETTS.

AUTOMATIC PIANO.

SPECIFICATION forming part of Letters Patent No. 731,089, dated June 16, 1903.

Application filed February 24, 1903. Serial No. 144,675. (No model.)

To all whom it may concern:

Be it known that I, PETER WELIN, a citizen of the United States, residing at Worcester, in the county of Worcester and State of Massachusetts, have invented a new and useful Automatic Piano, of which the following is a specification.

This invention relates to that class of automatic musical instruments which are controlled by rolls of perforated paper.

The especial objects of this invention are to provide an automatic piano or similar instrument in which the working parts may be entirely closed within the piano-casing, so that when not in use or when being played manually the automatic character of the instrument will not be apparent; to provide a simple and efficient automatic action which will produce more powerful effects than other instruments of this class; to provide for locking the keys when the instrument is being played automatically, and to arrange the parts of the completed instrument so that they may be readily removed for purposes of repairs or renewals.

To these ends this invention consists of the automatic musical instrument and of the combinations of parts therein, as hereinafter described, and more particularly pointed out in the claims at the end of this specification.

In the accompanying drawings, Figure 1 is a sectional view showing sufficient parts of a piano-action to illustrate the application of my invention thereto. Fig. 2 is a partial front view showing the relation of the paper-winding rolls and the tracker-board pipes. Fig. 3 is a fragmentary view illustrating the joints connecting the tracker-board pipes. Fig. 4 is an enlarged sectional view of one of said joints. Fig. 5 is a front view of a portion of the front of a piano-casing, the drop-slide being closed to conceal the paper-winding devices. Fig. 6 is a sectional view of the construction shown in Fig. 5. Fig. 7 is a perspective view of the drop-slide. Fig. 8 is a perspective view of the rock-shaft which operates the key-locking bar. Fig. 9 is a front view, partially broken away, of the lower panel of the piano-casing. Fig. 10 is a sectional view of the construction shown in Fig. 9, and Fig. 11 is a similar view showing the

bellows-operating pedals hung up inside the piano-casing.

To provide a mechanism for automatically playing a piano or similar instrument by the aid of perforated music-sheets, a number of automatic piano-players have been devised. In some of these automatic piano-players the operating devices are arranged in a separate instrument or housed in an entirely separate casing from the piano. Automatic piano-players of this class obstruct the keyboard of the pianos, necessarily occupy considerable room, and are regarded by many people as unsightly. In a number of constructions also it has been proposed to arrange the automatic playing devices so that they can be housed within the piano-casing. In all such constructions, however, with which I am familiar it has been necessary either to employ casings of special design or to disfigure and cut into ordinary piano-casings to considerable extents, and in all such constructions the automatic character of the instruments can be recognized at a glance.

One especial object of my present invention is to provide an automatic piano or similar instrument of that class in which the automatic action is housed within the piano-casing, but which will be so arranged that the automatic character of the instrument may, if desired, be entirely concealed, so that when the piano is not in use or when being played upon manually it will have the appearance of an ordinary upright or other type of piano, with nothing about the same which will indicate the presence of the automatic playing instrumentalities. To accomplish this result, the automatic action is divided into two groups of instrumentalities, the paper-winding devices being grouped together and arranged above the keyboard and behind the music-desk panel, while the pneumatics and bellows are arranged below the keyboard directly behind the lower front panel of the piano-casing. The tracker-board pipes, which connect these two groups of instrumentalities, extend laterally from the tracker-board to the sides of the piano before being carried down to the pneumatics. These tracker-board pipes are preferably provided with joints, so that the different lengths of

the pipes may be removed for renewals or repairs.

To secure powerful action, the pneumatics instead of being connected to operate the

5 keys are arranged to operate upon the abstracts through short multiplying-levers, so that the keys will not be required to be removed, and a leverage will be secured for striking the notes with more power.

10 When the piano is being played automatically, the keys are locked. The key-locking bar is preferably arranged to be released when the sliding door or panel is closed in front of the paper-winding devices.

15 The bellows-operating pedals are preferably mounted in a frame, which may be hung up inside the piano-casing, if desired, when not in use.

Referring to the accompanying drawings 20 by reference characters for a detail description of an automatic musical instrument embodying my invention, as shown most clearly in Fig. 1, A designates a key-lever pivoted on a pin *a* in the ordinary manner. At its 25 rear end the key A is provided with a pin engaging a thrust-rod or abstract B. The abstract B is pivoted at its upper end to the rocker C, which rocker C carries a trigger or jack D, operating a hammer H, and which 30 rocker C also operates the lever I, carrying the damper J, which normally engages the wire W.

The parts as thus far described will be recognized as an ordinary form of piano-action.

35 In applying my invention to such ordinary piano-action the pneumatic devices are preferably arranged below the keyboard. As shown herein, these parts comprise a base or channel-board 10, leading to which are the 40 tracker-board pipes 11, to be hereinafter referred to. Detachably clamped on the channel-board 10 are valve-casings 12, each of which carries a main or striking pneumatic 13. In this case I have illustrated the action 45 as including the pneumatics and valve-boxes, forming a bank or number of tiers, in which each valve-box and its pneumatic is independently removable. It is to be understood, however, that I do not desire to cover specifically 50 in this application for patent this detachable arrangement of individual pneumatics, as such subject-matter is claimed in an application for patent filed by me December 23, 1902, Serial No. 136,351. The movable section of 55 each of the pneumatics is connected by a link to a spring-pressed lever 14. Coöperating with each of the spring-pressed levers 14 is a screw-adjusted stop 15, which may be set to limit the striking motion of each pneumatic.

60 I regard the construction shown as a desirable one, because the pneumatics are accessible by simply removing the front panel of the piano-casing and the stops may be readily adjusted to secure the desired striking movements.

65 At their rear ends the spring-pressed levers 14 are connected by rods 16 to small multiplying-levers

ing-levers 17, each of said multiplying-levers being pivoted at one end in a frame 18 and being connected at its center to one of the abstracts B of the piano-action. 70

In practice I have found that by connecting onto the abstracts of a piano-action in this way I am enabled to secure more powerful and brilliant effects, while at the same time 75 the piano-keys are left stationary while the instrument is being played mechanically.

Coöperating with the piano-keys I preferably provide a spring-pressed lock-bar 19, which is held down by springs 20 when the piano is being played automatically, but which may be lifted by an operating-rod 21 when it is desired to play the instrument manually.

The connections between the tracker-board and the bank of pneumatics below the keyboard are most clearly illustrated in the second sheet of the drawings. 85

As shown in Fig. 2, the paper-winding mechanism of an automatic musical instrument constructed according to my invention may 90 comprise a tracker-board 23, over which the perforated paper may be drawn from a music-roll 22 and wound onto a winding-roll 24. These paper-winding devices are located in a box or compartment immediately over the 95 keyboard. Leading from the tracker-board 23 through the back of this compartment are the tracker-board pipes. The tracker-board pipes are divided into two groups 25 and 26, which separate and extend laterally to the 100 sides of the piano.

As shown in Fig. 3, the primary tracker-board pipes, as 25, are connected by boards 27 and 28, which are detachably clamped together to second lengths of tracker-board 105 pipe 29, which second lengths of tracker-board pipes 29 are connected by the boards 30 and 31, detachably clamped together, to the tracker-board pipe 11, before referred to—that is to say, in the construction herein 110 illustrated between each channel of the tracker-board and the pneumatic corresponding therewith I provide three lengths of tracker-board pipe, which are detachably connected by the joints or coupling before referred to. I regard this as a feature of advantage, as by means of this construction the parts may be more readily taken out for renewal or repairs without dismantling the 115 entire instrument. 120

The paper-winding devices are normally concealed behind a drop-panel or sliding door. The closing of this drop-panel is preferably relied upon for operating the connections for releasing the key-locking bar. The 125 constructions employed for this purpose are most clearly illustrated in the third sheet of the drawings.

As shown in Figs. 5 and 6, M designates a front panel or music-desk of the piano-casing. Sliding in the music-desk M is a drop-panel 32, which when closed normally conceals the paper-winding devices. The drop-panel 32 may be operated by a knob or han-

dle 33. On its rear face, as shown in Fig. 7, the drop-panel 32 is provided with a groove or channel 34, having a block or lug 35, co-operating with a spring-catch 36. When the 5 drop-panel is lifted, the spring-catch 36 will hold the same open, and extending down from the spring-catch 36 is a finger-button 37, which may be pushed up when it is desired to release the drop-slide, so as to permit the same to be closed. Extending up 10 from the drop-slide 32 is a cam 38, having an inclined face engaging the cranked end of a rock-shaft 39, which rock-shaft 39 is connected to the operating-rod 21 for lifting the 15 key-locking bar 19. By means of this construction, as shown most clearly by the dotted lines in Fig. 5, when the drop-panel 32 is closed the connections above described will raise the key-locking bar, so that the key-board 20 will be left free, permitting the instrument to be played manually, if desired.

The pedals or foot-controlled connections which are employed for operating the bellows are preferably arranged in a frame, 25 which may be hung up inside the piano-casing when not in use. This construction is illustrated most clearly in the fourth sheet of drawings.

As shown in Figs. 9 to 11, inclusive, P 30 designates the ordinary panel or base-board, which closes the front of the piano-casing below the keyboard. The lower part of the casing is substantially the same as that of an ordinary upright piano, except that the ped- 35 als are preferably in an arch or recess. Detachably secured in sockets in the piano-casing are the side arms 40 of a wire or metal frame. Pivoted on the front bar of the metal frame are treadles or foot-operated sections 40, connected by straps 42 to brackets 43, extending up from the movable sections 44 of the bellows.

When the piano is not being used or when it is not desired to operate the same automatically, the front panel P may be swung out 45 and the pedal-frame may be removed from the front of the piano and hung up on hooks 45 within the piano-casing, as illustrated in Fig. 11. I regard this as a desirable construc- 50 tion, because when the drop-panel is closed to conceal the paper-winding mechanism the hanging of the treadles within the casing will leave no indication of the automatic character of the piano.

I am aware that numerous changes may be 55 made in practicing my invention by those who are skilled in the art without departing from the scope thereof as expressed in the claims. I do not wish, therefore, to be limited to constructions I have herein shown and described; but

What I do claim, and desire to secure by Letters Patent of the United States, is—

1. In a construction of the class described, 65 the combination of a piano-action, comprising keys, an abstract operated from each key, main pneumatics, and operating connections

between each main pneumatic and its abstract, comprising a spring-pressed lever, a thrust-rod and a multiplying-lever connected 70 to the abstract.

2. In a construction of the class described, the combination of a piano-action, comprising keys, an abstract operated from each key, pneumatics, and connections between each main pneumatic and a corresponding abstract, 75 comprising a spring-pressed lever, a vertical thrust-rod, and a multiplying-lever pivoted at one end and having an abstract connected 80 thereto between the thrust-rod and the pivot of the lever, whereby the abstract will be operated with increased power.

3. In a construction of the class described, the combination of a piano-action, comprising 85 keys and parts operated thereby, pneumatic playing devices connected to operate other parts of the action without operating the keys and a spring-pressed locking-bar for locking the keys when the piano is being played au- 90 tomatically.

4. In a construction of the class described, the combination of a piano-action, comprising keys and parts operated thereby, pneumatic playing devices connected to operate other 95 parts of the action without operating the keys, a spring-pressed locking-bar for holding the keys stationary while the piano is being played automatically, and means for raising the locking-bar when the piano is to be played manu- 100 ally.

5. In a construction of the class described, the combination of a piano-action, comprising keys and parts operated thereby, pneumatic playing devices comprising a bank of 105 main pneumatics, spring-pressed levers operated by the pneumatics, an adjustable stop for limiting the motion of each of said levers, and connections from said levers to work other parts of the action without operating 110 the keys.

6. In a construction of the class described, the combination of a piano-action, automatic playing devices comprising pneumatics, pa- 115 per-winding devices, and a tracker-board controlling the pneumatics, a slide or door, and means for locking the piano-keys when the door is opened to allow access to the paper-winding devices.

7. In a construction of the class described, 120 the combination of a piano-action, automatic playing devices comprising pneumatics, pa- per-winding devices, and a tracker-board controlling the pneumatics, a vertically-movable panel or door, a spring-pressed locking-bar, 125 and means for releasing the locking-bar to lock the piano-keys when the door is raised to allow access to the paper-winding devices.

8. In a construction of the class described, 130 the combination of a piano-action, playing devices comprising pneumatics, paper-winding mechanism, and a tracker-board controlling the pneumatics, a drop-panel normally concealing the paper-winding devices, a spring-

pressed key-locking bar, a rock-shaft, a cam carried by the drop-panel for turning the rock-shaft to raise the locking-bar, and a detent for holding the drop-panel up after the same has been opened.

9. In a construction of the class described, the combination of a piano-action, automatic playing devices comprising pneumatics, paper-winding devices, a tracker-board and 10 tracker-board pipes connecting each channel of the tracker-board with a corresponding pneumatic, said tracker-board being located above the piano-keys, and the tracker-board

pipes extending laterally from the tracker-board to the sides of the piano, and thence 15 down to the pneumatics, each of said tracker-board pipes having joints formed by boards detachably clamped together.

In testimony whereof I have hereunto set my hand in the presence of two subscribing 20 witnesses.

PETER WELIN.
